[57] **CLAIM**

The ornamental design for a knife handle, as shown and described.

DESCRIPTION

FIG. 1 is a perspective view of a knife handle showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof;

FIG. 7 is a right side elevational view thereof;

FIG. 8 is a perspective view thereof, on a reduced scale; and,

FIG. 9 is a perspective view thereof, on a reduced scale.

The broken line showing of the blades in FIGS. 8 and 9 are for illustrative purposes only and form no part of the claimed design.
